UNITED STATES PATENT OFFICE.

ROBERT M. DIXON, OF EAST ORANGE, NEW JERSEY, ASSIGNOR TO SAFETY CAR HEATING & LIGHTING COMPANY, A CORPORATION OF NEW JERSEY.

LAMP.

SPECIFICATION forming part of Letters Patent No. 745,583, dated December 1, 1903.

Application filed February 21, 1903. Serial No. 144,425. (No model.)

To all whom it may concern:

Be it known that I, ROBERT M. DIXON, a citizen of the United States, residing at East Orange, Essex county, State of New Jersey, 5 have invented certain new and useful Improvements in Lamps, of which the following is a specification.

My invention relates to lamps, and has for its particular object to produce an improved 10 lamp of the cluster type, although the improvements are applicable to other forms of lamps.

In the accompanying drawing I have shown a deck-lamp embodying my invention, which 15 lamp is shown by way of illustration in order to clearly disclose the invention.

In the drawing, *a* indicates the body-casting, from which a suitable gasway-tube *b* is suspended, which gasway-tube is preferably 20 surrounded by a suitable spacing-piece *c* and an asbestos sleeve *d*.

The body-casting *a* is provided with a downwardly-extending sleeve or casing *e*, circumferentially apertured at *ff* for the passage of 25 air. The gasway-tube supports a suitable reflector-flange *g*, which reflector-flange supports an internal cylinder *h*, surrounded by a reflector *i*, which extends upward from the reflector-flange to a point just below the apertures *f*. A reflector-plate *j* is supported below the reflector-flange and above the cluster 30 *k*, supported from the gasway.

A series of flues *l* are arranged within the cylinder *h* and extend upward through the 35 lamp, one flue being located above each of the burners of the cluster and being adapted to carry off the products of combustion. These flues are seated at their upper ends in a top piece *m*. A deflector-plate *o* is located 40 above the chimneys or flues and is supported by a flue-post *p*, seated at its lower end in the body-casting *a* and passing through a sleeve *q* on the top piece. The flues are surrounded at their upper ends by a casing or 45 flue-cover *r*, apertured at or near its lower end with apertures *s*, which are protected by a flaring deflector or cinder-cap *t*. Supported from the body-casting is a suitable ring or support *u*, from which extend arms *v*, sup- 50 porting the top member *w* of a bezel or support ring, whose lower member *x* is hinged to

the upper member at *y* and provided with a suitable catch *z*.

A dome *1* and a globe *2* are supported by these rings or members. The lower ring is a 55 bezel-ring and is provided with a globe-supporting ring *3*, attached thereto by screws or otherwise, the inwardly-extending lip *4* of the globe being supported by the globe-supporting ring, there being preferably an asbestos or other non-conducting packing *5* interposed between the lip of the globe and the globe-supporting ring. When the lamp is in the form of a deck-lamp, as herein shown, a suitable ventilator *6* is provided outside of 60 the car and a frusto-conical thimble *7* extends between the decks *A* and *B* of the car-roof and delivers into the roof-thimble *8*.

Having described my invention, what I claim, and desire to secure by Letters Patent, 70 is—

1. In a lamp the combination of a main frame or support, a gasway suspended therefrom, a cluster-burner suspended from the gasway, a plurality of elongated draft-tubes 75 or chimneys *l* supported by the main frame and located above the lights of the cluster and a translucent inclosure for the burner and the lower ends of the draft-tubes the space within the translucent inclosure around the burner and the lower ends of the draft-tubes being entirely unobstructed.

2. In a lamp the combination of a cluster-burner, a series of separate independent elongated draft-tubes, a casing surrounding the 85 said draft-tubes, the said casing being apertured for the admission of air and a translucent inclosure for the burner and the lower ends of the draft-tubes the space within the translucent inclosure around the burner and 90 the lower ends of the draft-tubes being entirely unobstructed.

3. In a lamp the combination of a series of independent elongated draft-tubes or chimneys, a tubular reflector *i* extending below 95 and outside of the said chimneys, a cluster of burners located below the said chimneys and delivering their products of combustion into the said chimneys.

4. In a lamp the combination of a cluster-burner, a series of independent draft-tubes or chimneys, a deflector-plate *o* located above 100

the said chimneys and a translucent inclosure for the burner and the lower ends of the draft-tubes the space within the translucent inclosure around the burner and the lower 5 ends of the draft-tubes being entirely unobstructed.

5. In a lamp the combination of a plurality of chimneys, a perforated casing surrounding the same, a reflector also surrounding the said chimneys, a burner and a globe and dome surrounding the said burner, reflector and the lower ends of the said chimneys, the space within the said globe and dome being entirely unobstructed around the said reflector.

6. In a lamp the combination of a plurality of draft-tubes or chimneys, a tubular reflector extending below and outside of the lower ends of the said chimneys, a burner located below the chimneys and reflector, and

a translucent inclosure for the burner and the lower ends of the draft-tubes, the space within the translucent inclosure around the burner and reflector being entirely unobstructed.

25

7. In a lamp the combination of a plurality of draft-tubes or chimneys, a tubular reflector extending below and outside of the lower ends of the said chimneys, a burner below the said chimneys and a globe and dome surrounding the said burner, reflector and the lower ends of the said chimneys, the space within the said globe and dome being entirely unobstructed around the said reflector.
